H. SELLERS MCKEE, OF PITTSBURG, PENNSYLVANIA.

Design No. 2,825, dated November 5, 1867.

DESIGN FOR ORNAMENTING TABLE GLASSWARE.

The Schedule referred to in these Letters Patent and making part of the same.

TO ALL WHOM IT MAY CONCERN:

Be it known that I, H. S. MCKEE, of Pittsburg, in the county of Allegheny, and State of Pennsylvania, have invented or produced a new and original Design for the Ornamentation of Table Glassware; and I do hereby declare the following to be a full, clear, and exact description of the same, reference being had to the accompanying drawings, making a part of this specification, in which—

Figures 1, 2, and 3 represent respectively a spoon-holder, a butter-dish and cover, and a cream-pitcher, ornamented after my design.

My design for ornamenting table glassware consists of a fancy leaf upon a plain ground.

The ground A upon which the leaf is made is plain, and makes a good relief to the fancy leaf B, pressed thereon or therin. The leaves are deeply indented or scarfed, as at a, with tendrils b branching through them, and they are arranged so as to radiate from a common centre, as seen in the drawings.

The design intended to be claimed is specially shown within the red lines marked 1 2 3 4 in fig. 3.

What I claim as my invention or production, is—

The ornamentation of table glassware with a fancy leaf upon a plain ground, as herein described and represented.
